UNITED STATES PATENT OFFICE

2,488,990

DITCHDIGGING MACHINE

Luther B. South, Corpus Christi, Tex., assignor
of twenty per cent to Rogers F. Estes and thirty
per cent to Willie Bezdek, both of Corpus
Christi, Tex.

Application January 12, 1948, Serial No. 1,822

1. Claim. (Cl. 37—97)

This invention relates to a ditch digging machine where dirt is effectively removed and the possibility of any earth falling back into the ditch is obviated.

An object of the invention is to provide a machine which will operate to dig any desired ditch efficiently.

Another object of the invention is to provide means whereby the device is quickly connected to or detached from any tractor or jeep and is easily carried about from place to place.

A still further object of the invention is to provide a light machine, rigidly constructed and capable of use in narrow and usually inaccessible places, in trenching work for building foundations, or for digging shallow ditches for water and gas lines.

More specifically, a digging machine is provided with means to cut and scoop up dirt and convey it to one side of the ditch. Baffles to keep the dirt from falling back into the ditch are provided and means to regulate the depth of the ditch is included.

Other objects and advantages of the invention will hereinafter appear and for purposes of illustration but not limitation, an embodiment of the invention is shown in the accompanying drawings in which:

Figure 1 is a plan view of the ditch digging machine;

Figure 2 is a side elevation of the ditch digging machine;

Figure 3 is a vertical section taken along the line 3—3 of Figure 1;

Figure 4 is a sectional view as viewed in the direction of the arrows on Figure 3, and

Figure 5 is a horizontal section taken along line 5—5 of Figure 4, and shows a detail of the gage.

Referring to Figures 1 through 4, a frame 10 has welded to it a pair of side beams 12 and 14 which terminate a distance beyond one end of frame 10. Journaled to side beams 12 and 14, by means of shaft 16 is a ditch digging wheel 18 which includes along the outer periphery thereof a series of digging blades 20 which form cup or bucket-shaped portions 22 at the inner end. The wheel is braced by the usual spokes 24 at one side thereof and are reinforced by additional spokes 26 journaled to shaft 16. Within the inner perimeter of the wheel 18 and in close proximity thereto, is an arcuate guard 28 approximately equal to half the perimeter of the wheel and is secured to beam 14 by a support rod 32. The upper portion of the guard 28 is provided with

an inclined slide portion 30 disposed adjacent conveyor 34, soon to be more fully explained.

Referring to Figures 2 and 3, conveyor belt 34 travels around shafts 36 and 38 on an incline to the vertical and receives the dirt dug by blades 20 and retained in buckets or cups 22 by means of guard 28 from the slide 30 at its lower end and is carried away for a distance of about 2 feet before being dumped at the side of the ditch. Conveyor 34 is enclosed within two stepped guards 40 journaled at each end to shafts 36 and 38. One end 44 of the shaft 36 extends beyond guard 40 and a suitable sprocket 45 mounted on the end 44 of shaft 36 engages a chain drive 42 trained about a further sprocket 46. Supporting the shaft 16 for rotation is a gear housing 48, within which is mounted a gear supporting shaft 50, best shown in Figure 3. One end of the shaft 50 extends outwardly from the housing 48 and supports the aforementioned sprocket 46. A gear 52, within the housing 48 and secured to the shaft 16, engages a gear 53 on the shaft 50 for simultaneous rotation of the wheel 18 and the conveyor 34.

As best seen in Figures 4 and 5, an attachment 54 is provided in order to determine the depth of the ditch digging wheel 18. The attachment 54 includes outwardly tapering sides 56, 58 in order to both hold the dirt until picked up by the blades and cup and to prevent the dirt from pushing out. A flange 60 extends from the bottom of sides 56, 58 for contacting the ground. Welded to gage 54 are rods 62 slidable in collar 64, welded on beams 12 and 14, and locked against movement at 66. Thus, by adjustment of rod 62, the depth of the digging wheel 18 will be indicated.

Removably journaled to beams 12 and 14 is a transverse baffle 68 of Y-shape 70, 72 and held in position by means of pins 74, 76. The function of baffle 68 is to act as a guard and follow along the ditch just behind wheel 18, as is clearly shown in Figure 2, in order to enable bucket 22 again to pick up any dirt that may fall back into the ditch. Baffle 68 can be removed by pulling pins 74, 76 where such protection is not found necessary.

Referring to Figures 1 and 2, a pair of linking members 78 are retained in ears 80 welded to side beams 12 and 14 by locking means 82 and are adjustably connected at 84 to shaft 86 pivoted at 88 to a yoke 90. Yoke 90 is held on the inner side of a pair of shafts 100 by means of lock nuts 92. A shaft 94 is pivoted at 96 to the yoke 90 and is engaged by tractor 98 at the other end, as indicated in dotted lines in Figure 2. Shafts 100 are

telescoped within beams 12 and 14 to permit sliding movement when the digging wheel is raised from the supporting surface to facilitate transportation of the device from place to place. Shafts 100 are pivoted at 101 to the housing of tractor 98.

A power shaft 102 is connected by a universal joint connection 104, 106 to the shaft 50 and is connected at its other end to a power take-off (not shown), on tractor 98. A transverse angular tube 108 is welded to the top of frame 10 at its front end to provide clearance for shaft 86.

The operation of the device will now be described. Shaft 94 is pivotally connected at 110 to hydraulic means (not shown) on the tractor, thus enabling the ditch digging machine to be connected to tractor 98 and retained in operative or inoperative position by suitable controls (not shown). The machine is shown in inoperative position in dotted lines in Figure 2, and in operation in full lines. Shaft 86, connected to yoke 90 and ears 80 are moved upward by means of shaft 94 retained on yoke 90 and 96 and pivoted to tractor 98 and 110 when the device is not in use. By proper manipulation of hydraulic means (not shown) of tractor 98, the digging wheel is lowered to operating position. Shaft 100 telescopes within side beams 12 and 14 to compensate for changes in position.

Shaft 102 is connected to the power take-off of the tractor 98 and to the shaft 50 in order to rotate the chain drive 42, thus actuating the conveyor 34, and to also rotate the shaft 50 to thereby rotate the digging wheel 18. By this arrangement, the conveyor belt 34 will be rotated during rotation of the digging wheel 18. Blades 20 dig the ditch, the earth is carried upward in buckets 22 and retained by means of guard 28 until the upper level is reached. The dirt is then deposited on slide 30 and is carried away by conveyor 34 to be dumped at the side of the ditch. Gage 54 is adjusted by rods 62 to indicate the depth of the ditch to be dug and slides along the ground on flange 60. Baffle 68 is removably attached by pins 74, 76 to the rear of wheel 18 to prevent any dirt from falling back into the ditch.

It is obvious that numerous changes in details of construction, arrangement and operation may be effected without departing from the spirit of the invention especially as defined in the appended claim.

Having described the invention, what is claimed as new is:

In a ditch digging machine, a frame, a shaft carried by the frame, a ditch digging wheel mounted on said shaft and including a pair of spaced members, a plurality of circumferentially spaced digging blades fixed between said pair of spaced members, an arcuate guard and retainer plate secured to the frame and disposed radially inwardly of said digging blades to provide a sliding surface for material held on said blades, said guard and retainer plate having a downwardly and laterally inclined upper end portion constituting a slide, means for rotating the digging wheel, a conveyor mounted on the frame for receiving material discharged from the upper end portion of said guard and retainer plate, said conveyor having a lower end portion underlying the upper end portion of said guard and retainer plate, and attaching means for securing the frame to the hydraulic lift mechanism of a tractor, said attaching means comprising a U-shaped member having its ends pivoted to said frame, a rod terminally pivoted to said U-shaped member and to the lift mechanism of a tractor, a lateral projection at the central portion of said U-shaped member, a pair of rearwardly diverging tubular members having forward and rear end portions, the forward end portions of said tubular members being pivoted to said lateral projection, the rear end portions of said tubular members being internally threaded, a pair of link members pivoted to said frame, and a threaded connection between said link members and the internally threaded rear end portions of said tubular members, said frame including a pair of side members pivoted to a tractor frame and to the lift mechanism of a tractor.
